Primary Examiner — Derrick Holland*Assistant Examiner* — Lauren Calve(74) *Attorney, Agent, or Firm* — Renner, Kenner, Boisselle & Sklar, LLP(57) **CLAIM**

The ornamental design for a clothes hanger, as shown and described.

DESCRIPTION

FIG. 1 is a perspective view of a clothes hanger showing my design.

FIG. 2 is a front view thereof.

FIG. 3 is a right view thereof.

FIG. 4 is a rear view thereof.

FIG. 5 is a left view thereof.

FIG. 6 is a top view thereof; and,

FIG. 7 is a bottom view thereof.

The broken lines shown represent unclaimed subject matter and form no part of the claimed design.

1 Claim, 7 Drawing Sheets(56)
